UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed February 9, 1924. Serial No. 691,828.

This invention relates to improvements in anti-friction bearings.

One object of this invention is to provide an anti-friction bearing especially adapted for use on railway cars, and wherein the parts are so arranged that the anti-friction elements proper will return to normal position under the influence of gravity when the load is released.

- 10 Another object of my invention is to provide an anti-friction bearing, especially adapted for railway side bearings, so designed that a plurality of anti-friction elements are employed which are automatically returned to their normal position after being actuated, this returning movement being solely under the influence of gravity and without the aid of springs, counterweights or any other of the expedients heretofore found necessary, to the end that the anti-friction bearing is always in condition to operate for its full intended travel.

More specifically, an object of the invention is to provide an anti-friction bearing employing at least two rolling anti-friction elements, each of which is normally positioned at one extreme end of its path of movement, said elements being oppositely disposed so that one element will always be available for operation regardless of the direction in which the side bearing is actuated, and whereby said elements may be made automatically self-returning under the influence of gravity without the aid of springs or counterweights. By arranging these elements in alinement longitudinally of the bearing surface, I am enabled to use elements having a relatively wide bearing surface so that there will be no likelihood of crushing or otherwise injuring the elements under load.

Other objects and advantages of the invention will be apparent from the description and claims hereinafter following.

- 45 In the drawing forming a part of this specification, Figure 1 is a vertical sectional view, taken through the ends of the body and truck bolsters of a railway car, showing my improvements in connection therewith.

50 And Figure 2 is a vertical sectional view,

taken substantially on the line 2—2 of Figure 1.

In said drawing, 10 denotes the under portion of the body bolster of a railway car and 11 the upper portion of the truck bolster 55 opposed thereto.

Referring to the drawing, the improved side bearing is shown as applied to the truck bolster and comprises, broadly, a housing or retaining member A; a pair of anti-friction elements B—B; and a bearing plate C.

The housing A is of more or less box-like form, comprising side walls 12 and end walls 13, the latter being rounded so as to form end stops for the elements as shown, and the former having inwardly extending flanges 14 at their upper ends. The housing is provided with lateral extensions 16 at its ends whereby they may be secured to the truck bolster, or as shown in the drawing, for 70 securement to the bottom plate C by means of rivets 17, the bottom or bearing plate C being in turn mounted upon the bolster by any suitable means, as by rivets 18. The top and bottom of the housing are open, and the 75 anti-friction elements B are arranged in longitudinal alinement therein so as to roll toward one another and project through the open top end of the housing.

These elements B, which are of like size 80 and shape, are arranged in alinement longitudinally of the housing, each having trunnions 19 projecting outwardly from its axis, the flanges 14 of the side walls preventing the elements from being lifted outwardly 85 through the top of the housing. The top surface of the plate C is formed with an elongated bearing surface thereon that is inclined downwardly from the center thereof toward both ends, as indicated at 20, so as 90 to form a pair of inclined bearing surfaces for supporting the anti-friction rollers.

The operation of the bearing is as follows. Assuming that the loaded bolster 10 is moved to the left relatively of the bolster 11, 95 the anti-friction elements being in their normal position at the opposite ends of the housing and lying against the end walls thereof, the bolster 10 will engage the tops of both the anti-friction elements, but inas- 100

much as one of them is necessarily at its limit of movement in the direction in which the bolster 10 is moving, that element will remain stationary while the other element is free to move upwardly of its respective inclined bearing surface and will take the load, rolling upwardly of the inclined bearing surface. As soon as the load is released, the roller which has been actuated or rolled, will automatically return under the influence of gravity to its normal position, resting against the end of the housing. As the loaded bolster is moved in the reverse direction to that just described, that element B which formerly moved will remain fixed while the other element which formerly remained stationary will take the load and roll up its inclined bearing surface.

Thus it is seen that the elements are normally retained at the opposite ends of the housing and when the body bolster moves in one direction under load, only one of the roller elements will take the load to the end of its travel, the element taking the load depending upon the direction of movement of the loaded bolster.

As will be understood by those skilled in the art, the size of the rollers B and the length of the inclined surfaces 20 for each roller will be so proportioned that the maximum working travel for each roller will be allowed before engagement of the moving roller with the stationary roller.

It will be noted that the anti-friction rollers are of maximum length so as to provide a large bearing surface for taking and transmitting the load, and thus avoid any likelihood of crushing or becoming otherwise injured under heavy loads.

As pointed out in the description just preceding, only one of the rolling elements B carries the load during the actual operation of the side bearing, but nevertheless, it will be apparent that when the two bolsters approach each other under conditions of actual service and cause what is known as "pounding", such pounding will be taken by both of the elements B simultaneously, distributing this load over the maximum load taking area.

As hereinbefore described, the two elements B are made of the same size and shape so that there is possibility of the body bolster being in contact with both elements simultaneously when the bolster starts to move in one direction. It is also possible that due to unavoidable variations in manufacture and from wear, one of the elements B, as for instance, the left-hand element B, may be engaged slightly in advance of the right-hand element B as viewed in Figure 1 when the body bolster comes down and starts to move toward the left. In either case, however, the bearing will function properly, due to the fact that it is mounted on the

truck bolster, which in turn is resiliently supported by the bolster springs, which permit the truck bolster to tilt sufficiently to allow the body bolster to engage the proper element B firmly, and obviously the element that can be moved or rolled in the proper direction will be the one operated as the body bolster shifts relatively to the truck bolster.

I have herein shown and described what I now consider the preferred manner of carrying out my invention but the same is merely illustrative and I contemplate all changes and modifications that come within the scope of the claims appended hereto.

I claim:

1. In an anti-friction bearing for railway cars, the combination with a housing adapted for attachment to a truck bolster and having a bottom bearing surface that is inclined downwardly from the center to both ends; of a pair of anti-friction rollers normally arranged at the opposite lower ends of said inclined bearing surface, whereby only one of said rollers at a time will take the load to the end of travel and roll upwardly when the body bolster moves relatively to the truck bolster.

2. In an anti-friction bearing, the combination with a support; of a pair of rollers carried by said support, said rollers being engageable with a co-operating bearing surface which is relatively movable with respect to said support; means on said support for positively limiting movement of one of said rollers in one direction; means for displacing said roller toward said bearing surface upon movement of said roller in a direction away from the movement limiting means; means for positively limiting movement of the other roller in said last named direction; and means for displacing said last named roller toward said bearing surfaces when moved in a direction away from the movement limiting means co-operating therewith.

3. In an anti-friction bearing, the combination with a support; of movable rollers carried by said support; means for positively limiting movement of one of said rollers in one direction and for positively limiting movement of the other roller in the opposite direction; and a bearing surface on said support for each roller, said bearing surfaces being inclined upwardly away from said means for positively limiting movement of the rollers.

4. In an anti-friction bearing, the combination with a housing; of a plurality of anti-friction rollers within the housing, said rollers being relatively movable toward each other lengthwise of the housing; means for positively limiting the extent of longitudinal separation of said rollers; means for elevating each of said rollers when moved away

from said limiting means by contact with an actuating member to maintain contact of said actuated roller with the actuating member and break contact between the other roller and the actuating member, said displaced roller being free to return to the normal separated position due to the action of

gravity when contact between said roller and the actuating member is broken.

In witness that I claim the foregoing I ¹⁰ have hereunto subscribed my name this 5th day of February, 1924.

JOHN F. O'CONNOR.
